TON HARDWARE CO., OF SOUTHBINGTOM, CONNECTICUT, A CORPORATION.

METAL HANDLE FOR TROWELS.

1,369,762.

Specification of Letters Patent. Patented Feb. 22, 1921.

Application filed October 18, 1920. Serial No. 417,724.

To all whom it may concern:

Be it known that I, GEORGE L. CURTISS, a citizen of the United States, residing at Plantsville, in the county of Hartford and State of Connecticut, have invented a new and useful Improvement in Metal Handles for Trowels; and I do hereby declare the following, when taken in connection with the accompanying drawings and the characters of reference marked thereon, to be a full, clear, and exact description of the same, and which said drawings constitute part of this application, and represent, in—

Figure 1, a plan view of a trowel provided with a metal handle constructed in accordance with my invention.

Fig. 2, a side view of the same.

Fig. 3, a side view of the inner end of the handle portion detached.

Fig. 4, an underside view of the same.

Fig. 5, a sectional view on the line 5—5 of Fig. 1, enlarged.

This invention relates to an improvement in metal-handled trowels, and by the term trowels I wish to be understood as including masons' trowels of all characters, garden trowels, and other similar implements.

The object of this invention is to provide a trowel with a strip metal handle so arranged as to give the necessary strength, and the invention consists in the construction as hereinafter described and particularly recited in the claim.

In carrying out my invention I employ a trowel blade 10 of any approved design according to the purposes for which it is to be used. The handle is formed from a strip of metal doubled to form a loop grip 11, and the ends are brought together to form a shank 12. The end 13 of the upper portion of the strip is riveted to the upper face of

the blade and the other end 14 has a bearing on the face of the blade closely adjacent to the end 13 and so that the upper and lower portions of the handle stand in the same vertical plane. Preferably, and as shown, the loop handle is corrugated to give strength and to form a grip handle, and preferably the end 13 will be drawn to form integral studs 15 by which the handle may be riveted to the blade or the end 13 may be punched to form holes for rivets. The strip thus provided with integral studs is bent to form the handle and the studs are passed through holes formed for them in the trowel blade 10 and upset therein so as to firmly rivet the handle to the blade, or it may be secured by separately-formed rivets, and when so riveted the end 14 of the handle bears upon the face of the blade just in rear of the riveted end 13, so as to form a rigid handle. I am thus enabled to produce at a very low cost of manufacture and in a very simple manner a trowel provided with a metal handle, the advantages of which over wooden handles are generally recognized.

I claim:

A trowel provided with a metal handle, said handle formed from a strip doubled to form a loop grip, one end of the strip riveted to the trowel blade and the other end of the strip brought to a bearing on the face of the blade adjacent to the riveted end both portions of the handle standing in the same vertical plane.

In testimony whereof, I have signed this specification in the presence of two subscribing witnesses.

GEORGE L. CURTISS.
